STEAM LOCOMOTIVE.

Application filed April 9, 1923, Serial No. 630,979, and in Sweden September 28, 1922.

The quantity of steam required for driving a locomotive is subject to continued variations. At times the train is standing at a station, at times it must be rapidly started and brought up to full speed, at times the train has an up-grade to surmount, at times it is being braked on a down-grade etc. As the water space of the boiler used is very small in all existing constructions, there is practically no equalization between the heat produced by the fire or the generation of steam and the steam consumption. The fire must, consequently, follow the variations in the steam consumption almost exactly. A slight equalization may be effected by introducing cold water into the boiler at times when the steam pressure is rising. It is true that this measure is always taken in locomotive service, but it must be considered to be wrong in principle, as great variations in the water level can not be allowed in boiler constructions as now in use. If the water level falls too much, there is danger of explosion and, should it rise too high, water is carried over into the cylinders. Furthermore since the water level in the boiler is subject to continued local variations due to the slope of the track, variations in the rate of speed of the train etc., it is evident that the variations in said water level must not be unnecessarily increased beyond the inevitable ones.

Under present conditions the management of the fire on a locomotive is very difficult on account of the necessity of paying regard to the average water level and its local variations mentioned above, keeping the pressure from falling too much, and keeping the safety valves from blowing. Almost without exception such blowing occurs on the train while stopping at the stations. It is readily seen, that this must be the case in a rationally effected driving, with the arrangements in use at present since a considerably greater quantity of steam is required to start a train than is necessary in regular operation. Therefore it will not suffice that the pressure in the boiler is high immediately before the start. The generation of steam or the power of the fire must also in this instant be so

great that the boiler is capable or continuously delivering the necessary quantity of steam, without the pressure falling. Now if it is impossible immediately before the start to feed cold water into the boiler, which feeding however, as stated above, can not last but for a short time, there remains no other possibility than to let the safety valves blow, which results in every great losses of heat. Nevertheless, this manner of operation is used in all existing locomotives, a really practical arrangement for effecting an equalization between the heat supply and the steam consumption having not hitherto been suggested.

The present invention has for its object to avoid above outlined inconveniences and losses and to effect the equalization mentioned above between the heat supplied in the furnace or the generation of steam and the steam demand of the steam engine, whereby the firing of the locomotive can be more rationally effected than is now the case.

The invention consists in an arrangement which enables surplus of steam from the locomotive boiler to be conducted to a stor'er arranged on the locomotive or on its tender or on any other car connected to the locomotive, said stor'er consisting of a well insulated receptacle partly filled with water, in which receptacle the steam is allowed to condense and from which feed water is supplied to the locomotive boiler.

The water space of said stor'er is connected with the steam space of the boiler by means of a piping in which an over-flow valve is inserted, said valve being so constructed and arranged that it opens and lets through the surplus of steam into the stor'er, should the pressure of the piping in front of the valve, that is the pressure of the locomotive boiler, rise beyond a certain value.

Moreover the water space of the stor'er is connected with the water space of the locomotive boiler by means of a conduit in which a pump is provided by means of which feed water from the stor'er may be forced into the locomotive boiler.

The steam space of the locomotive boiler

is connected with the water space of the storer and with the steam motor in such a way that the boiler is able to supply steam either only to the storer or only to the steam motor or simultaneously to both.

In order to facilitate starting of the locomotive and to obtain greater power in up-grades etc. the steam motor is preferably connected with the steam space of the boiler 10 and with that of the storer in such a way that steam may be simultaneously obtained from the boiler as well as from the storer, or only from one of them. In certain cases for instance it is possible to have the locomotive standing cold, while nevertheless, the storer is charged, and thereby it will be possible to perform certain shunting work and the like with steam from the storer.

Moreover, the steam motor is connected 20 with the water space of the storer in such a way that exhaust steam from the steam motor can be conducted to the storer should this be found suitable in some case or other.

Said arrangement relieves the fireman of 25 the care of the water level in the boiler, as he need no longer vary said level for the purpose of equalizing said variations to some extent, but he is able to set the water level in such a way as to answer the requirements regarding the safety of the boiler 30 and the driving of the engine. At the same time, he need not fear that the safety valve will easily blow, as is now the case. Further, the firing is facilitated by this invention, it being not necessary to force it as 35 much as now is the case. Other advantages are also involved by the use of this invention, among which the following may be mentioned.

40 A considerable increase in the efficiency of the boiler or a decrease in the fuel consumption is obtained caused partly by the fact that the fire need not be constantly controlled, as is now the case, by opening and closing the dampers, and partly by the temperature of the feed water becoming considerably higher than hitherto. Therefore, the fire need not be forced as much as is now the case which, of course, is of advantage to the fuel economy.

50 By the feed water being warm the possibility of increasing the generation of steam, without it being necessary to force the fire, is considerably increased. This is easily understood by the following:

The temperature of the feed water is at present behind the injector about 40° C. If this temperature is increased to 186° C., the quantity of heat given off by the fire is decreased according to the relation

$$\frac{728 - 186}{728 - 40} = \frac{542}{688} = 0.79$$

(728 cal. being the total heat of steam at 65 10 atm. pressure and 300° C. which is an

average condition of operation for modern locomotives). If the driving power is the same, the intensity of the firing can consequently be decreased by about 20%, or if the fire is the same, the generation of steam 70 can be increased by

$$\frac{1}{0.79} = 1.27 \text{ or } 27\%.$$

Since we have already reached the limit 75 with respect to the size of the grate area and of the heating surface, the advantage thus gained is evident.

A very considerable saving of steam is effected due to the fact that the steam escaping through the safety valve may be supplied to the storer and may thus, ultimately, be used to the benefit of the boiler. Further saving of steam may be made by the firing being less forced, as will be described hereinbelow, whereby the pressure may be maintained higher and the specific consumption of the boiler is decreased.

The train can be brought to the desired 90 rate of speed much more rapidly than is now the case, and also develop a greater speed on the line, this being an advantage of not the least importance under the present circumstances. This depends partly on the fact that before starting, up-grades or the like, it is possible to maintain the fire at a greater intensity without fearing that the safety valve will blow, and partly on the fact that the feed water has the same temperature as the water in the boiler and therefore the necessary feeding of water does not, in long up-grades, bring about a decrease in the generation of steam, as is now the case.

The water level in the boiler can always 95 be held normal and, therefore it is always possible to prevent water from being entrained into the cylinders and also to obviate any danger of explosion (especially in down-grades of the line) which may arise.

100 The management of the fire will be considerably simplified. It is known that with the arrangements now in use, proper co-operation with the driver and accurate knowledge of the route to be travelled are necessary factors for enabling the fireman to succeed reasonably well in performing his duties. In using the storer above referred to he need not at all be anxious to exactly fix the time for forcing the fire before an up-grade or a start, nor, on the other hand, to finish firing immediately before the top of an up-grade, all such irregularities being compensated for by the storer without corresponding losses of heat.

105 On account of the fact that the capability of the boiler to generate steam is increased by about 27%, the fire need not be forced as frequently as before, and thereby the quantity of broken-coal carried away on forced

service will be considerably reduced. Great losses are thus avoided.

It happens often that a leakage occurs in the boiler on account of the cold water fed into the boiler sinking down to the bottom of the boiler where it causes leaks, especially at the lower part of the fire box. As the feeding according to the invention is performed with water of the same temperature as that in the boiler, this disagreeable drawback is of course eliminated. For the same reason the durability of the locomotive or of the boiler will be increased and the necessity of repairs is reduced. For the same reason the danger of fire by ignition through sparks is also lessened and the cleanliness on the train is improved.

As a last advantage it may be mentioned, that the water by being heated in the storers is freed from sediment which often may be troublesome for the operation of the boiler, the evaporating capacity of the heating surface and the durability being thus increased.

In the accompanying drawings, Fig. 1 is a longitudinal elevation of a locomotive and tender embodying my invention, drawn partly in section, showing the more important features of my invention in heavy lines, certain minor features in lighter lines and, for sake of clearness, omitting parts which are old and obvious.

Fig. 2 is an elevation of the forward end of the tender shown in Fig. 1.

Fig. 3 is a diagram of the parts in Figs. 1 and 2, serving to more readily explain the invention.

Fig. 4 is a cross section of a pressure operated valve controlling introduction of cold water into the storers to condense the steam therein, thus lowering the pressure and heating the water.

Fig. 5 shows an indicator for indicating the water level in the storers.

Fig. 6 is a cross section of an overflow valve.

In Figs. 1, 2 and 3, M designates the locomotive boiler from the steam dome of which a pipe L₁ extends to an insulated storers A preferably arranged on the tender T, said storers being filled in part with hot water of a temperature and a pressure somewhat lower than those of the boiler.

The steam pipe L₁ opens close to the bottom of the said storers into the water space, and the steam is distributed by means of nozzles K. In the upper part of the storers, a number of spray-nozzles S are arranged, to which the water is supplied by means of the injector J through the conduit L₂ from the cold feed water receptacle W on the tender. Inserted in the conduit L₁ are a non-return valve B and a so-called over-flow valve V₁, the latter being separately shown in Fig. 6. This valve is operated in response to the pressure in front of the same, in pipe L₁, that

is the boiler pressure and is adjusted to open and blow off the steam not actually consumed but formed in the boiler, into the storers A, at a pressure lying 0.1 or 0.2 kg. below the pressure at which the safety valve of the boiler blows, such steam being condensed in the storers. By reason of this, the pressure of the storers will rise somewhat. Extending from the storers is a smaller conduit L₃ which controls the valve V₂, said valve being so constructed that it opens the conduit L₄ supplying steam to the injector when the pressure in the storers has nearly risen to the boiler pressure, for instance to 2 kg. below said pressure, the valve V₂ then admitting steam to the injector J, which sucks cold water from the water receptacle W of tender T, the cold water in the storers A then condensing the steam entering through the conduit L₁. It is evident that thereby an approximately constant pressure is always obtained in the storers A, said pressure being determined by the valve V₂ and the same being preferably so regulated as to be about 1 to 2 kg. below the boiler pressure.

In such a way, the conduit L₁ will not be too large. On the other hand, a difference of pressure of 2 kg. corresponds, with the locomotive pressures used, only to a difference of temperature of 5° centigrade. As the storers operate between the temperature of the tender, which is 0° to 15° centigrade, and approximately 185° centigrade, this difference of 5° centigrade has practically no influence upon the size of the storers. With a view to ensuring safety, however, the storers are preferably constructed for the same pressure as the boiler.

The water level in the storers is evidently a measure of the quantity of steam which is condensed in its water space for the time being, and there is an entirely constant relation between the water level and the quantity of condensed steam.

C designates the cylinders of the locomotive which are supplied by steam from the boiler by means of pipe 10. A pipe 11 connects the steam space of the storers with the cylinders so that steam may be supplied to the cylinders from the storers. A check valve 12 in pipe 11 prevents flow of steam in pipe 11 towards the storers. Pipe 13 permits exhaust steam from the cylinders to pass into the storers.

Steam pump P forces water from storers A into the boiler M through L₅.

Indicator t, shown more in detail in Fig. 5 is operated by float n and indicates the height of water in the storers A. As above explained this indicates the amount of steam stored in storers A. Indicator e, more specifically shown in Fig. 6 indicates the amount of opening of overflow valve V₁.

Fig. 6 shows the above-mentioned overflow valve on an enlarged scale. This valve

is, as described above, inserted in the conduit L_1 and the steam flows in the direction indicated by the arrows of the figure. The pressure in front of the valve is caused to 5 actuate the diaphragm a , said pressure being counter-balanced by a spring b . The diaphragm a is connected to the valve spindle c to which the valve cone d is attached. If the pressure in front of the valve rises 10 beyond a certain value, the force actuating the diaphragm a will be greater than the reaction force of the spring b , and therefore the spindle c , together with the valve cone d , will rise, the valve being opened so as to 15 admit steam to the storer.

The position of the valve cone d may be read off on an indicator e connected to the spindle c . Consequently, it is possible on 20 said indicator, if suitably graduated, to read off directly the quantity of steam flowing to the storer.

In Fig. 4, a valve V_2 is shown on an enlarged scale, said valve being inserted in the conduit L_4 (see Fig. 3) through which 25 steam may be admitted to the injector J . If the pressure in the storer rises, said pressure will actuate the diaphragm f which is counter-balanced by the spring g . If the storer pressure on the diaphragm f becomes 30 greater than the power with which the spring g acts on the same, the valve h opens, and the pressure of the storer will then actuate the piston i which is then moved upwards against the action of the spring k , 35 whereby the valve l is opened and steam is admitted to the injector J which feeds water from the water receptacle on the tender to the distributing nozzle S in the storer, causing the pressure in the storer to fall.

40 Moreover, at the place of the fireman, a distance water-level indicator according to Fig. 5 is preferably arranged whereby he is able to read off the water level in the storer at every moment and thus to find out the 45 state of charge of the storer at the same time. This water-level indicator consists of a float n which is arranged in the storer and pivoted by means of the lever o about the point p connected with a segment q . Attached to said 50 segment is a wire r which passes through a pipe s to an indicator t mounted at the place of the fireman.

The management of a locomotive is not 55 complicated by these arrangements but is, on the contrary, considerably simplified. The fireman soon acquires the habit of regulating the water level in the receptacle A in such a way that the storer will always contain a sufficient amount of water, when required, while on the other hand, that it does not contain too much water. For instance, 60 immediately before a station the water level in the storer should not be higher than that the steam generated by the fire during the 65 stop, and condensed in the storer together

with the water required for this purpose, may find place in the storer. On the other hand, the fireman has always the possibility of determining from the position of the over-flow valve V_1 how much steam is supplied to the storer on any occasion. 70

If sometimes the fireman has not the proper water level in the storer, this eventuality does not, of course, involve any risk as is the case when regulating by means of the 75 water level of the boiler.

In the receptacle, much more steam may be stored than in the boiler, by varying the water level, it being possible to select one having a size of from 4 to 6 m^3 even when using an existing tender. The boiler of the Swedish fast train locomotives has a water surface of about 6 m^2 . As a variation in the water level of 100 mm. must be considered to be the highest allowable, only $0.1 \times 6000 = 80$ 85 600 liters of water or

$$\frac{600}{4} = 150 \text{ kg.}$$

of steam may be stored in the boiler, while 90 in the storer with a volume of say 4 m^3 ,

$$\frac{4000}{4} = 1000 \text{ kg.}$$

95 may be stored, that is 6.7 times more. There should be experienced no difficulty in making the storers still larger, if desired. For alpine railways, special tenders should be provided.

A fast train locomotive having a steam 100 consumption of approximately 10,000 kg. per hour in normal service, or about 167 kg. per minute, the storage in the boiler will only last for

$$\frac{150}{167} = 54 \text{ seconds,}$$

whereas the storage in the storers will last for

$$\frac{1000}{167} = 6 \text{ minutes,}$$

110 From this it will be seen that a storers of the said size is more than sufficient to take up all the steam generated by the fire during normal stops at a station, without it being necessary to damp the fire. 115

The storers should preferably be placed on the tender as described above. In new structures, it may be disposed in the fore part of the locomotive in front of the boiler, or it may be arranged in a saddle-like fashion over the boiler. When placing the storers on the tender, steam as well as water may be transmitted between the storers and the 120 boiler by means of flexible pipes of known type.

125 The boiler and the storers may be coupled in parallel, as stated above, in such a way that steam from both may be conducted to 130

the steam motor. In order to render such coupling possible, only a non-return valve is required in the piping between the storers and the connecting pipe between the locomotive boiler and the steam motor.

What I claim as new and desire to secure by Letters Patent of the United States of America is:—

1. A locomotive comprising a boiler having a steam and water space, driving cylinders, a storers under pressure having a steam and water space and a varying water level, a pipe connecting the steam space of the boiler with the cylinders, means to conduct steam from the steam space of the boiler to the storers and mingle the steam with water in the storers and means to conduct water from the storers to the boiler.

2. A locomotive comprising a boiler having a steam and water space, driving cylinders, a storers under pressure having a steam and water space and a varying water level, a pipe connecting the steam space of the boiler with the cylinders, a pipe connecting the steam space of the boiler with the storers, means to conduct water from the storers to the boiler and a pipe connecting the steam space of the storers with the cylinders.

3. A locomotive comprising a boiler having a steam and water space, driving cylinders, a storers under pressure having a steam and water space and a varying water level, a pipe connecting the steam space of the boiler with the cylinders, conducting means to conduct steam from the steam space of the boiler to the storers and mingle the steam with water in the storers, a valve in the said conducting means operated in response to boiler pressure and means to conduct water from the storers to the boiler.

4. A locomotive comprising a boiler having a steam and water space, driving cylinders, a storers under pressure having a steam and water space and a varying water level, a pipe connecting the steam space of the boiler with the cylinders, a pipe connecting the steam space of the boiler with the storers, a valve in the last mentioned pipe operated in response to boiler pressure, means to conduct water from the storers to the boiler and means to conduct steam from the storers to the cylinders.

5. A locomotive comprising a boiler having a steam and water space, driving cylinders, a water receptacle, a storers under pressure having a steam and water space and a varying water level, a pipe connecting the steam space of the boiler with the storers, a valve in said pipe, means to actuate said valve in response to boiler pressure, said means being so adjusted that said valve opens upon rise of pressure above a predetermined value and admits the surplus of

steam generated to the storers, an indicator showing the position of said valve, a pipe connecting said water receptacle with said storers, mechanism to force water through the last mentioned pipe, a pipe leading steam to said mechanism to operate the same, a second valve in the last mentioned pipe, means to operate said second valve in response to the pressure in the storers and so adjusted that the second valve opens when the pressure in the storers has risen above a predetermined value somewhat lower than the previously mentioned predetermined value, an indicator showing the height of water in the storers, means to conduct steam from the steam space of the boiler to the driving cylinders, and means to conduct water from the storers to the boiler.

6. A locomotive comprising a boiler having a steam and water space, driving cylinders, a water receptacle, a storers under pressure having a steam and water space and a varying water level, a pipe connecting the steam space of the boiler with the storers, means to control flow of steam through said pipe, a pipe connecting said water receptacle with said storers, mechanism to force water through the last mentioned pipe, a pipe leading steam to said mechanism to operate the same, a valve in the last mentioned pipe, means to operate said valve in response to the pressure in the storers and so adjusted that the valve opens when the pressure in the storers has risen above a predetermined value, an indicator showing the height of water in the storers, means to conduct steam from the steam space of the boiler to the driving cylinders, and means to conduct water from the storers to the boiler.

7. A locomotive comprising a boiler having a steam and water space, driving cylinders, a water receptacle, a storers under pressure having a steam and water space and a varying water level, a pipe connecting the steam space of the boiler with the storers, a valve in said pipe, means to actuate said valve in response to boiler pressure, said means being so adjusted that said valve opens upon rise of pressure above a predetermined value and admits the surplus of steam generated to the storers, a pipe connecting said water receptacle with said storers, mechanism to force water through the last mentioned pipe, means to control said mechanism in response to the pressure in the storers, an indicator showing the height of water in the storers, means to conduct steam from the steam space of the boiler to the driving cylinders, and means to conduct water from the storers to the boiler.

8. A locomotive comprising a boiler having a steam and water space, driving cylinders, a water receptacle, a storers under pressure having a steam and water space and a

varying water level, a pipe connecting the steam space of the boiler with the water space of the stor'er, means to control flow of steam through said pipe, a series of nozzles

5 in said storers, a pipe connecting said water receptacle with said series of nozzles, mechanism to force water through the last mentioned pipe, means to control said mechanism in response to the pressure in the
10 storers, an indicator showing the height of water in the storers, means to conduct steam from the steam space of the boiler to the driving cylinders, and means to conduct water from the storers to the boiler.

15 9. A locomotive comprising a boiler having a steam and water space, driving cylinders, a water receptacle, a storer under pressure having a steam and water space and a varying water level, a pipe connecting the steam space of the boiler with the storer, means to control flow of steam through said pipe, a pipe connecting said water receptacle with said storer, mechanism to force water through the last mentioned pipe, means to control said mechanism in response to the pressure in the storer, an indicator showing the height of water in the storer, means to conduct steam from the steam space of the boiler to the driving cylinders, and means to conduct water from the storer to the boiler.

20

25

30

10. A locomotive comprising a boiler having a steam and water space driving cylinders, a water receptacle, a storer under pressure having a steam and water space and a varying water level, a pipe connecting the steam space of the boiler with the storer, means to control flow of steam through said pipe, a pipe connecting said water receptacle with said storer, mechanism to force water through the last mentioned pipe, means to control said mechanism in response to the pressure in the storer, means to conduct steam from the steam space of the boiler to the driving cylinders, and means to conduct water from the storer to the boiler.

50 11. A locomotive comprising a boiler having a steam and water space, driving cylinders, a water receptacle, a stor'er under pressure having a steam and water space and a varying water level, a pipe connecting the steam space of the boiler with the water space of the stor'er, a valve in said pipe, means to actuate said valve in response to boiler pressure, said means being so adjusted that said valve opens upon rise of pressure above a predetermined value and admits the surplus of steam generated to the stor'er, an indicator showing the position of said valve, a series of nozzles in said stor'er, a pipe connecting said water receptacle with said series of nozzles, mechanism to force water through last mentioned pipe, an indicator showing the height of water in the stor'er, means to conduct steam

from the steam space of the boiler to the driving cylinders, and means to conduct water from the store to the boiler. 65

12. A locomotive comprising a boiler having a steam and water space, driving cylinders, a water receptacle, a storer under pressure having a steam and water space and a varying water level, a pipe connecting the steam space of the boiler with the water space of the storer, means to control flow of steam through said pipe, a series of nozzles in said storer, a pipe connecting said water receptacle with said series of nozzles, mechanism to force water through the last mentioned pipe, means to conduct steam from the steam space of the boiler to the driving cylinders, and means to conduct water from the storer to the boiler.

13. A locomotive comprising a boiler having a steam and water space, driving cylinders, a water receptacle, a stor'er under pressure having a steam and water space and a varying water level, a pipe connecting the steam space of the boiler with the stor'er, means to control flow of steam through said pipe, a pipe connecting said water receptacle with said stor'er, mechanism to force water through the last mentioned pipe, means to conduct steam from the steam space of the boiler to the driving cylinders, and means to conduct water from the stor'er to the boiler.

14. A locomotive comprising a boiler having a steam and water space, driving cylinders, a water receptacle, a storer under pressure having a steam and water space and a varying water level, a pipe connecting the steam space of the boiler with the storer, means to control flow of steam through said pipe, a pipe connecting said water receptacle with said storer, mechanism to force water through the last mentioned pipe, means to conduct steam from the steam space of the boiler to the driving cylinders, means to conduct water from the storers to the boiler, and a pipe to conduct steam from the storers to the cylinders. 100 105 110

15. A locomotive comprising a boiler having a steam and water space, driving cylinders, a water receptacle, a stor'er under pressure having a steam and water space and a varying water level, a pipe connecting the steam space of the boiler with the stor'er, means to control flow of steam through said pipe, a pipe connecting said water receptacle with said stor'er, mechanism to force water through the last mentioned pipe, means to control said mechanism in response to the pressure in the stor'er, means to conduct steam from the steam space of the boiler to the driving cylinders, means to conduct water from the stor'er to the boiler, and a pipe to conduct steam from the stor'er to the cylinders. 115 120 125

16. A locomotive comprising a boiler, storer to the boiler and means to lead cold driving cylinders, a storer under pressure having a steam and water space and a varying water level, means to conduct steam from the boiler to the storers, means to conduct steam from the boiler to the driving cylinders, means to conduct water from the

therein rises above a predetermined value. 10
In testimony whereof I affix my signature.

JOHANNES RUTHS.
